UNITED STATES PATENT OFFICE.

PETER H. FERRIER, JR., OF CHICAGO, ILLINOIS.

DOOR BOLT.

1,418,143.

Specification of Letters Patent. Patented May 30, 1922.

Application filed February 23, 1921. Serial No. 447,057.

To all whom it may concern:

Be it known that I, PETER H. FERRIER, Jr., a citizen of the United States, residing at Chicago, in the county of Cook and State of Illinois, have invented certain new and useful Improvements in Door Bolts, of which the following is a specification.

This invention relates to improvements in bolts for double swinging or sliding doors.

10 The primary object of the invention is the provision of a bolt for securely locking doors, and the details of which bolt have been so designed as to cooperate in requiring a minimum of space.

15 A further object of the invention is the provision of a door bolt of the above described character, which is specifically adapted for use upon double folding or sliding doors; said bolt extending longitudinally of 20 one of said doors, and of such design as to be of minimum thickness, thus requiring no cutting or mutilation of any of said doors, in order to receive said bolt.

25 A further object of the invention is the provision of a device of the above described character, the details of which can be cut or stamped from stock parts, to provide a durable, economic, and efficient door bolt.

30 Other objects and advantages will be apparent during the course of the following detailed description.

35 In the accompanying drawings forming a part of this specification, and in which similar reference characters designate corresponding parts throughout the several views,

Figure 1 is a perspective view of a pair of folding doors having the improved bolt construction mounted thereon.

40 Figure 2 is an enlarged fragmentary elevation, partly in section, showing details of construction of said bolt.

Figure 3 is a fragmentary front elevation, showing parts in section, of details of said bolt.

45 Figure 4 is a plan view partly in cross section showing a guiding member associated with said bolt construction.

50 Figure 5 is a perspective view showing a detail of construction.

In the drawing, wherein for the purpose of illustration, is shown the preferred embodiment of my invention, the letter A designates a door casing, or similar structure, 55 defining a door opening, and having the door structure B foldably or slidably disposed

therein. A bolt structure C is operably disposed upon said door structure B and which includes the crank disc member D pivotally mounted upon the door structure B; a bolt member E pivotally connected to said disc member D; and a guide member F mounted upon said door B, and adapted to guide movement of the bolt C.

The door structure B may be of any approved construction, and in the present instance comprises a pair of doors 10 and 11 hingedly connected together at 12, the door 11 being hingedly connected at 13 to one side of the door casing A. While this structure specifically embodies swinging doors, it is to be understood that the bolt C may be used in conjunction with any door construction. However, the bolt C has been provided primarily for use in connection with the folding doors 10 and 11, such as are in general use at the present time, in garages and the like, where a relatively wide door opening is desirable, and where it would be impractical to use a single door for closing 80 said door opening.

Since in most instances, it will be desirable to have a bolt upon the inside of the door structure B, and in view of the fact that the doors 10 and 11 fold outwardly, it can 85 be readily seen that the bolt structure must be disposed intermediate the doors 10 and 11 when the same are in folded position. This of course necessitates a bolt structure of minimum width and in many instances, 90 it has been found necessary to cut away parts of the doors, and otherwise mutilate the same in order to accommodate the bolt structure. To this end the bolt structure C has been provided, and which is of minimum 95 width, sufficient to be comfortably accommodated intermediate the doors 10 and 11.

The bolt C is preferably mounted upon the outer free door 10, preferably adjacent the hinged connection with the door 11, in 100 order to provide the most effective locking condition.

The disc D is pivotally mounted upon the bolt 15, and spaced from the inside 16 of the door 10, by a wear plate 17. Said bolt 105 15 is preferably inserted transversely through the door 10 with the head 18 overlying the outside of the door, whereby the disc D may be pivotally mounted upon the shank 19 of the bolt 15, and a nut 20 may be 110 adjustably mounted upon the screw threaded end of the shank 19 and be adjustably spaced

to permit oscillation of said disc or member D. The member D is substantially circular in formation, stamped from a flat piece of metal, and includes the disc proper 21, and 5 a handle 22. The disc 21 and handle 22 are uniform in thickness throughout the member D. An aperture 23 is provided centrally of the disc 21, and which aperture receives the shank 19 and the bolt 15. Suitable apertures 24 are provided upon opposite sides of the aperture 23, the same, of course, being eccentric with respect to pivotal mounting of the disc 21 upon the bolt 15. The apertures 24 and aperture 23 are in alignment. 10 15 The bolts E are of special construction, and it is preferred that a pair of the bolts be used in each bolt construction C. Since the bolt construction C is adapted for use longitudinally of a door, each of the members E are consequently substantially equal to one-half the length of said door. The members E are tubular in formation, being preferably cut from standard lengths of tubing or pipe; each of said members E being slotted upon the longitudinal center, and inwardly from one end thereof, to provide a recess 25 extending inwardly from an end 20 25 30 35 40 45 50 55 60 upon each side of which recess the remaining portion of tubing provides arms 27. In assembling the bolt members E to the disc 21 of the member D, the recesses 25 of said members E receive the disc portion 21; the members E being disposed upon opposite sides of the central aperture 23, in such manner that the apertures 28, which are stamped in alignment in the arms 27, align with the apertures 24. A pivoting member 30 is then inserted for pivotally connecting the members E to the disc 21 through apertures 24 therein, and said members 30 have their ends peened over, or countersunk into the apertures 28, in order that there shall be no projection of the pivoting rivet 30 from sides of the member E. Both of the members E are connected in the above described manner to the discs 21 and in the apertures 24 thereof. In this manner the members E are eccentrically pivoted upon the disc 21. It should be noted in this connection, that the wear plate or disc 17 is of the same thickness as the legs or arms 27, and since the member D is operably disposed upon the longitudinal centers with respect to said member E, it can be seen from an observation of Figure 2 of the drawings, that none of the combined details of construction of the member D and members E are of greater thickness upon the inside 16 of the door 10 than the thickness of the members E themselves.

The guide members F are of special construction, having been designed to accord with the general principles for which the bolt structures C have been provided, 65 namely, conservation of space, and to this

end, a base plate 35 is adapted for stationary disposal upon the inside 16 of a door 10, by means of screws 36 or the like inserted through suitable countersunk apertures 37 in said base member 35. A guide ring 38 is provided having an internal circumference 39 adapted to reciprocably receive the members E and which is of just sufficient diameter that said members E can be reciprocated comfortably therein. Since 75 during operation of the members E they oscillate as well as reciprocate, it is desirable that the ring guide 38 be oscillatively disposed within the base plate 35. A shank 40 is therefore provided, which has a countersunk head thereon, whereby said shank 40 may be rotated, or oscillatively disposed within a suitable aperture 41, centrally of the base plate 35.

In operation, the disc D, the members E 85 and the guides F having been properly assembled, substantially as illustrated in Figure 1, upon the door structure B, upon oscillation of the disc 21 by the handle 22, the members E will be advanced or retracted 90 from the top and bottom of the door structure B. Suitable keepers G may be provided in the floor, or in the upper door casing A adapted for receiving the extreme free ends of the bolt members E when the same 95 are advanced for locking the door B in closed position, said keepers G are of course provided with apertures 45 therein for receiving said free ends of the bolt members E.

Thus a bolt construction C has been provided, in which the members E can be advanced or retracted by oscillation of the member D, and in this connection, it should be noted that the downmost or most inwardly retracted position of the bolts E are 105 definitely defined by means of contact of the external circumference 46 of the disc 21, with the inner or bottom surfaces 47 of the recesses 25, and which position is best illustrated in Figure 3. In like manner, the 110 open position of the bolts E is determined by the handle 22 abutting the upper bolt member E, when said bolts E are in advanced position in their keepers G. Thus no undue strain, or rupture of parts is 115 likely to occur due to excessive operation or strain upon the member D.

While sliding bolts operating and eccentrically disposed upon pivoted discs have been designed and used heretofore, it is to 120 be understood that this invention has been designed and provided primarily to conserve space intermediate adjacent folding doors 10 and 11, and to this end cooperating parts of the bolt structure C have been 125 designed, and perfected, to occupy a minimum of space.

Various changes, in the shape, size and arrangement of parts, may be made to the form of my invention herein shown and 130

described, without departing from the spirit of the invention or the scope of the claims.

I claim:

1. In a door bolt, the combination with a door, of a bolt member provided with a slot extending inwardly upon the longitudinal center thereof, a crank disc centrally pivoted upon said door, said bolt eccentrically pivoted upon said disc in said slot, whereby said bolt will be advanced or retracted upon oscillation of said disc, and a rocking guide member for said bolt.

2. In a door bolt, the combination of a bolt member, means for oscillatively advancing and retracting said bolt, and an oscillative guiding means for said bolt.

3. In a door bolt, the combination of a bolt member, means for oscillatively advancing and retracting said bolt, and means for guiding said bolt including a stationary base, and a guide member oscillatively mounted in said base.

4. In a door bolt, the combination with a door, of a disc member pivoted at its center upon said door, said disc having a handle integral therewith, a pair of bolts, each having a pair of arms upon an end thereof to provide a recess, means eccentrically pivoting said disc within the recesses of said

bolt, and upon opposite sides of said disc pivot, to oscillatively advance and retract said bolts upon oscillation of said disc, and oscillative guiding means for each of said bolts.

5. In a door bolt, the combination with a pair of folding doors provided for closing a passageway, of a crank member pivotally connected upon one of said doors, said crank member including a substantially circular disc, and a handle integral therewith, means spacing said disc from said door, a pair of bolts pivotally connected to said disc upon opposite sides of its door pivot, for reciprocation by oscillation of said disc, said bolts provided longitudinally upon an end thereof with a recess adapted to receive said disc for pivotal movement, guide members for the free ends of said bolts including a stationary base plate detachably mounted upon said door, and a guide ring member oscillatively mounted in said base plate for reciprocably receiving said bolt members, said guide members defining the maximum thickness of any of the associated parts of said bolt structure upon said folding door.

PETER H. FERRIER, JR.
